UNITED STATES PATENT OFFICE.

WILLIAM H. MANNS, OF WAYNESBORO, PENNSYLVANIA, ASSIGNOR TO FRICK COMPANY, OF WAYNESBORO, PENNSYLVANIA, A CORPORATION.

ICE-MAKING APPARATUS AND PROCESS.

1,159,058.

Specification of Letters Patent.

Patented Nov. 2, 1915.

Application filed March 7, 1910. Serial No. 547,717.

To all whom it may concern:

Be it known that I, WILLIAM H. MANNS, a citizen of the United States, residing at Waynesboro, in the county of Franklin and State of Pennsylvania, have invented certain new and useful Improvements in Ice-Making Apparatus and Processes, of which the following is a specification.

My said invention consists in certain improvements in a block plate freezing apparatus and the process employed, whereby blocks of ice may be frozen of a commercial size and thickness in a much shorter period of time than required by the use of the system and process heretofore commonly employed, and at the same time make ice which will be free from impurities and sediment, all as will be hereinafter more fully described and claimed.

Referring to the accompanying drawings which are made a part hereof and on which similar reference characters indicate similar parts, Figure 1 is a top or plan view of an ice freezing tank and adjacent parts embodying my improved system, portions being broken out, so that only short sections at each end of each tank are shown, for the purpose of enabling the parts to be illustrated on as large a scale as possible, and part of the cover being removed to show the interior structure, Fig. 2 a view partly in longitudinal section and partly in side elevation of the apparatus as shown in Fig. 1, Fig. 3 a detail section on an enlarged scale

through a freezing cell and the adjacent freezing plates, illustrating the parts more clearly, Fig. 4 a side elevation of a portion of a cake of ice as after removed from the freezing cell, Fig. 5 a side elevation of one of the anchor plates, Fig. 6 a cross section through the freezing tank on a line passing through a freezing plate or brine cell, Fig. 7 a similar view through the freezing cell showing the thaw pipes, and Fig. 8 a similar view through the freezing cell showing the air agitating pipes and anchor plates as when in position for the freezing operation.

The general construction of the freezing tank and other parts of the apparatus is, or may be, of a well known or any approved form suitable for this system of freezing. The brine cells C and C' are composed of side plates connected by bottom plates c from which they extend to the top of the tank. The side plates of each of the several brine cells stand somewhat at an angle, the

cells being slightly narrower at the top than at the bottom, so that the freezing cells between said brine cells are slightly narrower at the bottom than at the top. The end 60 brine cells C are formed with their outside plates vertical and their inner plates inclined and the other brine cells C' located at intervals throughout the length of the freezing tank are inclined on both sides, as 65 shown. This form of the brine cells provides a freezing cell between them from which the cake of ice, after being frozen, can be more readily removed. The adjacent sides of the brine cells are that distance 70 apart which is desired shall be the full thickness of the cake of ice. As shown, the apparatus is arranged to freeze ice 12 inches thick, 12 feet long and 3½ feet high.

In Fig. 8 I have shown five space and 75 anchor plates 1, 2, 3, 4 and 5 which in the operation, are frozen into the cake and are intended to serve as a ready means for dividing the cake into 6 equal parts as well as anchors to which means may be attached for 80 lifting the cake out of the freezing tank, eyes being formed on the top end of plates 1 and 5 for this purpose. Said plates are each formed with large central openings or slots to permit the horizontal circulation 85 of the water, as will be hereinafter described. I have shown two freezing tanks separated by a narrow space or partition P and filters F are arranged at the adjacent ends of each tank.

In Fig. 1 I have indicated a cold brine tank 10, a cold brine pump 11, a brine cooler 12, a warm brine tank 13, a warm brine pump 14 and a system of pipes leading to the brine cells, freezing cells, and filters, 95 whereby water is supplied, filtered, agitated and the freezing medium provided for the operation as will now be outlined. The water to be frozen is supplied to the freezing cells through the header 20 and branch 100 pipes 25. It is circulated by the operation of the pump 21 which draws it from the freezing cells through branch pipes 22 into headers 23 and suction pipe 24 to said pump and forces it through the pipes 26 into the filters F and out through the pipes 27 into the headers 20 and back into the opposite ends of the freezing tanks through the branch pipes 25, or vice versa. The air coming in under pressure through the air header 110 15 is forced through the branch pipes 28 into pipes 29 which are located centrally in

the bottom of each freezing cell and formed with perforations at intervals through which the air can escape upwardly into the water and rise in the form of bubbles to its surface keeping the water agitated and causing, by such agitation, the precipitation of any sediment or impurities therein. The vertical agitation by the air and the cross agitation or circulation of the water by means of the pump 21 causes the impurities and sediment to be deposited in the bottom of the freezing cell and be carried by the cross circulation out of the freezing cell and into the filters where such impurities are removed and the filtered water returned, thus insuring the freezing of clear and perfect ice. The brine is forced by the cold brine pump 11 from the cold brine tank 10 through the brine cooler 12 into the header 30 from which it is supplied to the freezing cells through the branch pipes 31. The brine is discharged from each branch pipe 31 through perforations in a vertical pipe 32 into one end of the brine tank and overflows from the opposite end through a branch pipe 33 into a header 34 which connects to a return pipe 35 leading back to the cold brine tank 10. The freezing process in the apparatus shown is carried on by the circulation of the cold brine as above outlined. The freezing continues until the ice formed on the sides of the adjacent plates of the adjacent brine cells meets in the center of the freezing cells and the two formations join and freeze solidly together forming a solid block of ice filling each freezing cell from side to side. Said ice may then be freed from the freezing plate by stopping pump 11 and discontinuing the circulation of the freezing medium and forcing the warm brine, by means of pump 14, from the warm brine tank 13 through the pipe 16 into the header 30. Thaw pipes 40 also are connected by branch pipes 41 with header 30 being provided with valves 42 by which communication with said header may be cut off or established as desired. One of said pipes 40 extends down behind the end plate of each freezing cell on one side thereof across to the opposite end of said cell beneath the bottom plate of said freezing cell, then up behind the plate at the opposite end of said freezing cell, on one side thereof, where it turns and is returned to the starting point parallel with the first described branch but near the opposite side of the plates. After the freezing operation is concluded the cold brine pump 11 is stopped, the valve closed between the pipes leading from the brine cooler to header 30 and the cold brine allowed to flow out of the brine cells (when forced out by the inflow of other brine) through header 34 and pipe 44 back into the cold brine tank which is located on a level below said brine cells. The valves

are then opened to establish communication between the warm brine supply pipe 16 and header 30 and the thaw pipes 40. The warm brine pump 14 is then started and the warm brine circulated through the brine cells and thaw pipes 40 until the blocks of ice are thawed free from the plates forming the walls and bottom of the freezing cells. The lifting and carrier mechanism, which is commonly an ordinary crane provided for the purpose is then connected with the eyes in the tops of the anchor plates 1 and 5 and the blocks of ice are hoisted out of the freezing cells and carried to the place of storage, or use, in any ordinary or approved manner. Thaw pipes 40 are preferably emptied during the freezing operation.

By this method and apparatus ice may be frozen into solid blocks of pre-determined dimensions and weight in approximately one-third the time required by the process heretofore commonly in use, inasmuch as the freezing continues until a solid block is formed entirely filling said cell, and this result is made possible by the provision for the agitation of the water which maintains the freezing thereof while the water is in active circulation and under conditions such as commonly prevail in the freezing of natural ice. The formation of the freezing cells enables the freezing to continue until said cells are solidly frozen and renders the removal of the solid blocks practical and of ready accomplishment.

Having thus fully described my said invention, what I claim as new and desire to secure by Letters Patent, is:

1. An ice making apparatus comprising a freezing tank divided into brine cells and freezing cells, said freezing cells being formed slightly flared from their bottoms to their tops, a system for circulating the freezing medium and thawing medium through said apparatus, and means for supplying water to said freezing cells between the converging walls thereof and imparting and maintaining a horizontal flow of the water between said cells during the process of freezing, substantially as set forth.

2. An ice making apparatus comprising a freezing tank, ice freezing cells formed therein between vertical freezing plates or brine cells, means for supplying water to the freezing cells and circulating the same horizontally therein, means for circulating a freezing medium, means for circulating a thawing medium, and an air agitating system comprising perforated pipes located in the bottom of the freezing cells and connected with air supply pipes, substantially as set forth.

3. An ice making apparatus comprising a freezing tank divided by freezing plates into a series of freezing cells, means for circulating a freezing medium, means for circulating a thawing medium, a water supply sys-

tem for the freezing cells comprising a system of pipes on one side of the tank for supplying said water and a system of pipes on the opposite side for draining said water 5 from said cells, means for maintaining a circulation of said water through said pipes and horizontally through said cells, and an air agitating system comprising perforated pipes located in the bottom of the freezing 10 cells and connected with air supply pipes, substantially as set forth.

4. An ice making apparatus comprising a freezing tank divided into a series of freezing cells by freezing plates or brine cells, 15 means for circulating a freezing medium through said freezing plate, means for circulating a thawing medium around said freezing cells, an air agitating system arranged to discharge in the bottom of said freezing 20 cells and a water circulating system arranged to circulate the water horizontally through said freezing cells, substantially as set forth.

5. An ice making apparatus comprising a freezing tank divided into freezing cells by hollow freezing plates or brine cells, means for circulating a freezing medium through 25 said freezing plates, means for circulating a thawing medium around said freezing cells, 30 means for circulating the water to be frozen horizontally through said freezing cells, and means for agitating said water vertically by discharging air under pressure into the bottom of said freezing cells, substantially as 35 set forth.

6. An ice making apparatus comprising a freezing tank, freezing plates or brine cells arranged transversely across said freezing tank at intervals throughout its length, a 40 freezing medium supply system, a thawing medium supply system, and air agitating system arranged to discharge into the bottom of the freezing cells, a water supply system for said freezing cells comprising filters, and means for circulating the water 45 from said filters through said freezing cells and back through said filters, substantially as set forth.

7. An ice making apparatus comprising a freezing tank divided into freezing cells by vertical freezing plates, means for conducting a freezing medium, means for conducting a thawing medium around said freezing cells, a water system for circulating 50 water horizontally through each of said freezing cells separately, means for agitating the water in a direction substantially at right angles to the circulation thereof, and filters interposed in said system between the 55 discharge from said freezing cells at one side and the inlet to said freezing cells at the opposite side, substantially as set forth.

8. An ice making apparatus comprising a freezing tank divided into freezing cells by freezing plates arranged a distance apart 65 equal to the thickness of the block of ice to be formed, means for conducting a freezing medium through said freezing plates, means for conducting a thawing medium around said freezing cells, and means for agitating 70 the water to be frozen in said freezing cells comprising a pipe with perforations in its top located in the bottom of said freezing cells and connected with an air supply, substantially as set forth.

75 9. An ice making apparatus comprising a freezing tank divided into freezing cells by freezing plates arranged a distance apart equal to the thickness of the block of ice to be formed, means for conducting a freezing medium through said freezing plates, means for conducting a thawing medium around said freezing cells, anchor plates located at intervals in each of said freezing cells, part of said plates being formed with 80 means for attachment thereto, and means for circulating the water to be frozen through said freezing cells, substantially as 85 set forth.

10. The process of forming ice, which consists in actively circulating the water to be frozen in one direction through the freezing cells of an ice making apparatus and directing air through said circulating water in a direction across the direction of its circulation and substantially at right angles thereto, whereby said water is agitated during the freezing operation, substantially as 90 set forth.

100 11. The process of forming ice which consists in circulating the water to be frozen horizontally through the freezing cells of a freezing tank of an ice making apparatus and agitating said water vertically by discharging air upwardly therethrough from 105 the bottom of the freezing cells, substantially as set forth.

110 12. The process of forming ice comprising the circulation of the water to be frozen in a horizontal direction between the freezing plates in the freezing tank of an ice making apparatus and the agitation of said water by discharging air under pressure in a vertical direction from the bottom of said freezing tank, substantially as set forth.

115 In witness whereof, I have hereunto set my hand and seal at Waynesboro, Pennsylvania this 23rd day of February, A. D. nineteen hundred and ten.
